(57) **CLAIM**

The ornamental design for a handle, as shown and described.

DESCRIPTION

In a preferred embodiment, the nature of this product is as a handle suitable for removably holding a cleaning pad.

FIG. 1 is a right, top, front perspective view of a handle embodying our new design;

FIG. 2 is a front elevational view thereof, the rear elevational view thereof being identical to the front elevational view shown;

FIG. 3 is a left side elevational view thereof, the right side elevational view thereof being identical to the left side elevational view shown;

FIG. 4 is a top plan view thereof;

FIG. 5 is a bottom plan view thereof; and,

FIG. 6 is a bottom plan view thereof, but showing some additional environment positionable on the bottom surface of the handle.

The broken line depiction of hook type fastener material in FIGS. 5 and 6 is for purposes of illustration only, and forms no part of the claimed design.
